UNITED STATES PATENT OFFICE.

RICHARD B. OWEN, OF WASHINGTON, DISTRICT OF COLUMBIA.

DESIGN FOR AN ELECTRIC-STORAGE-BATTERY CONTAINER.

58,938.

Specification for Design.

Patented Sept. 6, 1921.

Application filed April 1, 1921. Serial No. 457,824. Term of patent 14 years.

To all whom it may concern:

Be it known that I, RICHARD B. OWEN, a citizen of the United States, residing at Washington, in the District of Columbia, have invented a new, original, and ornamental Design for Electric-Storage-Battery Containers, of which the following is a specification, reference being had to the accompanying drawing, forming a part thereof.

Figure 1 is a perspective view of my new design for electric storage battery containers, and

Fig. 2 is a vertical longitudinal section of the same.

I claim:

The ornamental design for an electric storage battery container substantially as shown.

RICHARD B. OWEN.
